(57) CLAIM

The ornamental design for a battery, as shown and described.

DESCRIPTION

FIG. 1 is a front, top, right perspective view of a battery showing my new design,

FIG. 2 is a front elevation view thereof,

FIG. 3 is a rear elevation view thereof,

FIG. 4 is a view of the right side elevation view thereof,

FIG. 5 is a view of the left side elevation view thereof,

FIG. 6 is a top plan view thereof; and,

FIG. 7 is a bottom plan view thereof.

The broken lines depict portions of the battery that form no part of the claimed design.

1 Claim, 5 Drawing Sheets
